SYSTEM OF BROADCASTING

Application filed November 17, 1927. Serial No. 233,801.

This invention relates to the transmission of intelligence by radiant energy and more particularly to systems of broadcasting information, music, etc.

One object of this invention is to provide a system of broadcasting in which two classes of service may be rendered, one intended for the general type of receiving station over which there is no supervision except that given by the operator and the other a service of relatively better quality in which the service and maintenance may be supervised.

Further objects of this invention are to provide an improved system for transmitting energy comprising a sending system arranged to emit energy in the form of a series of carrier waves or oscillations, preferably of a high superaudible frequency modulated by a series of waves of lower but superaudible frequency the latter series of waves being modulated by desired signals such for example as voice waves; and to provide an arrangement for the selective reception of either or both of said modulated oscillations and the transformation of the energy thereof into sensible manifestations.

Further objects of the invention will appear from the following description taken in connection with the accompanying drawings in which:

Fig. 1 is a diagram of one form of a sending station constructed in accordance with this invention;

Fig. 2 is a diagram showing the relationship of the emitted frequency components;

Fig. 3 is a diagram of a receiving station arranged to give one class of service and to cooperate with the sending station of Fig. 1; and,

Fig. 4 is a diagram of a receiving station arranged to give a different class of service, and is also to cooperate with the sending station of Fig. 1.

Referring to Fig. 1, one embodiment of the invention comprises any suitable source of high frequency electrical oscillations producing a carrier wave. The source shown in this instance includes the three electrode thermionic device 10, which may be referred to hereinafter as the master oscillator or carrier

wave oscillator. The device 10 is of the usual construction including a plate 12 upon which the electrons impinge, and a grid 13 for controlling the flow of electrons. These parts are connected in the interrelated inductively coupled circuits, comprising a transformer having windings 14, 15 and 16 which are connected in the plate, grid and output circuits respectively, in such a manner that the energy in the plate circuit reacts on the grid circuit so as to cause the device to oscillate regeneratively. The plate 12 is maintained at a positive potential relative to the filament 11 by means of the usual "B" battery 27, the positive terminal of which is connected through the inductance 28 to the plate. There is thus produced an oscillatory current of relatively high frequency, for instance a frequency of 1,000,000 oscillations per second, the said frequency being determined by the electrical constants of the inter-related circuits, particularly the capacities of the condensers 17 and 18, which it is understood may be varied as desired.

For producing oscillations of relatively lower but supersonic frequency, there is provided a second three electrode thermionic device 20 having the usual filament 11, plate 12 and grid 13, and connected in a regenerative circuit comprising a transformer having windings 22, 23, and 24 which are connected in the plate, grid and output circuits respectively. The plate 12 is maintained at a positive potential with respect to the filament by means of the battery 27 the positive terminal of which is connected through an inductance 29 to the plate. This regenerative circuit is provided with suitable condensers 25 and 26 the capacity of which may be adjusted so that oscillations of a predetermined frequency, relatively lower than those of the master oscillator 10 are generated.

The audio frequency modulator 34 is of the usual well known construction comprising the filament 11 adapted to be supplied by the common "A" battery 21, the plate 12 upon which the electrons are adapted to impinge, and the control electrode or grid 13 for controlling the flow of electrons and which is adapted to be supplied through the trans-

former 8 with the audio frequency or signal current. The battery 7 is provided in the grid circuit of said device, the effective potential of which with respect to the grid is 5 adapted to be varied by means of the secondary of the transformer 8 in accordance with the audio frequency signals. The plate 12 of the device 34 is adapted to be supplied through the audio frequency choke coil 9, by 10 the high potential source 27.

The intermediate modulator 35, of the usual construction, is adapted to be supplied with filament current by the "A" battery 21. The input of the device 35 is supplied through 15 the coil 24 and the high potential source 27 supplies the plate 12 through the audio frequency choke 9, previously mentioned, and the radio frequency coil 30 shunted by the condenser 32.

20 Inductively coupled to the inductance 30 is inductance 31 shunted by the condenser 38 and included in the plate circuit of the thermionic modulated radio frequency amplifier 36. Also included in the plate circuit of 25 said device is the inductance 37. The output of the amplifier 36 is adapted to be supplied to the circuit comprising the condenser 38 and the inductance 39 shunted by the condenser 40. The antenna 41 is supplied through the 30 inductance 42 and completes its circuit, to the ground 44, through the variable tap 43 on the inductance 39, the position of which tap may be varied to obtain proper resonance.

Having now described the transmitter of 35 my invention I will briefly describe its operation. The input 8 of the audio modulator tube 34 serves to impress upon the grid of said tube the audio frequency with which it is desired to modulate the intermediate frequency. The output of the modulator tube 34 is connected to the source of high potential 40 27 through the usual audio frequency choke 9. The intermediate modulator tube 35 thus has impressed upon its plate a potential varied in accordance with the audio frequency signals and therefore serves to amplify the intermediate frequency oscillation, in a manner which is modulated in accordance with the audio frequency signals. Included in the plate circuit of the intermediate modulator tube 35 is an intermediate frequency choke composed of inductance 30 and condenser 32. Inductively coupled to this 45 intermediate frequency choke is a similar intermediate frequency choke, composed of inductance 31 and condenser 38, and included in the plate circuit of the modulated frequency amplifier 36 so as to vary the potential impressed upon the plate of said amplifier 50 55 tube and thus vary the total amount of transmission. Consequently the output of the tube 36 is modulated at intermediate frequencies only since there is no audio frequency voltage component impressed upon the plate circuit of this tube and it, therefore, by 60 65

means of the tank circuit composed of the condenser 40 and inductance 30 and the antenna circuit, serves to radiate the carrier frequency and two side bands formed by the modulation of the carrier frequency by the intermediate frequency generated by generator 20 and modulated in accordance with the audio frequencies.

Referring to Fig. 2 and assuming that the frequency of the generator 20 is 40,000 cycles per second, and that the voice currents include a frequency range of from 200 to 2000 cycles per second, there will be produced in the output circuit of the modulator a series of oscillations having a frequency of 40,000 cycles per second and also of two side bands, comprising a lower band containing a plurality of series of oscillations varying in frequency from 38,000 to 39,800 cycles inclusive and an upper band containing a plurality of series of oscillations varying from 40,200 to 42,000 cycles per second inclusive. Then assuming that the frequency of the generator 10 is 1,000,000 cycles there will be produced in the output circuit a series of oscillations of a frequency of 1,000,000 and also two side bands one comprising frequencies of from 958,000 to 962,000 cycles per second and the other of from 1,038,000 to 1,042,000. This figure shows the relationship of these frequencies to each other, C indicating the carrier frequency, B and B¹ the upper and lower side band stations and A and A¹ the audio frequency side band components.

It will be obvious from the above and from the description of the transmitter that it would be possible to receive the transmission by either of two separate and distinct methods. The first method by receiving the carrier frequency C detecting and obtaining therefrom either sideband B or B¹ then detecting the sideband and obtaining the audio frequency components A, and the second method simply by tuning an ordinary receiver to the sideband B or B¹ and detecting and obtaining the audio frequency A.

For using the first method of transmission, a receiver such as is shown in Fig. 3 is utilized. A receiving element is positioned so as to intercept the waves transmitted from the sending system of Fig. 1. As shown, this receiving element comprises an antenna 60, the circuit of which includes an inductance 61 coupled to a closed oscillatory circuit 62, comprising an inductance 63 and a variable condenser 64.

For detecting the energy received by the open aerial circuit 60, 61, the closed oscillatory circuit 62, is connected to the input circuit of the three electrode thermionic detector 66 of well known construction, having the usual filament 11, plate 12, and grid 13. The filament 11 may be heated by a current supplied by a battery 70, the amount of current being controlled by a variable rheostat 71.

In shunt with the filament 11 is a potentiometer 65 having a slider 73 connected with the closed oscillatory circuit 62, whereby the normal potential maintained upon the grid 13, relative to the filament 11, may be adjusted. For regenerative or reflex purposes the inductance 72, which is variably coupled to the coils 61 and 63, is provided in the output circuit and for transmitting purposes the said circuit includes the primary winding 75 of an intervalve transformer 74. A by-pass condenser 76 is in shunt with the primary winding 74 to permit of the passage of high frequency oscillations. For maintaining a positive potential upon the plate 12 relative to the filament 11, a high potential battery 77 is included in the plate circuit.

A second potentiometer 79 is connected across the filament heating battery 70 and includes a slider 80 connected to one end of the secondary winding 78 of the transformer 74. A variable condenser 81 forms with the winding 78 a closed oscillatory circuit 93, which is connected so as to control the three electrode thermionic device or secondary detector 82 which is of well known construction, and includes the usual filament, grid and plate. The filament is arranged to be heated by current from the battery 70 in the usual manner.

The output circuit of the secondary detector 82 is connected to an indicating device, in this case a telephone receiver 83, shunted by a by-pass condenser 84. This output circuit also includes a connection between the indicating device and the positive terminal of the high potential source 77.

In the form of receiving station shown in Fig. 4, which is for use with the second method of transmission as explained above, there is provided a receiving element consisting for example, of an antenna 90, the circuit of which includes an inductance 91 coupled to a closed oscillatory circuit 92 comprising an inductance 93 and a variable condenser 94. This closed oscillatory circuit 92 is operatively connected to the input of a three element thermionic device 96 through a suitable grid condenser 97 and grid leak 98 connected in shunt with each other. The thermionic device comprises a conventional grid plate and filament, the filament being heated by a battery 100 and the current being regulated by a rheostat 101.

The output or plate circuit of the device 96 includes an indicating device 83 shunted by a high frequency by-pass condenser 84 and a plate potential battery 107 for maintaining a positive potential on the plate with respect to the filament.

In the operation of the receiving station of Fig. 3 the radiant energy having a composite character, hereinbefore described, is emitted from the sending station of Fig. 1 and is in-

tercepted by the open aerial circuit 60, 61. As a result there is produced in the closed oscillatory circuit 62, oscillations corresponding in frequency to the continuous waves generated by the master oscillator 10, the said closed oscillatory circuit 62 being tuned to be responsive to the radiated energy of the sending station. The slider 73 is so adjusted that the thermionic device 66 operates on the curved portion of its characteristic curve and thus the device 66 acts to rectify or otherwise detect the above described oscillations and thereby produce in the output circuit of the detector unidirectional impulses having the intermediate frequency produced in the transmitter by the oscillator 20. The output circuit transmits these detected or rectified oscillations through the inductance 72 which is adjustably coupled with the inductance 61 so that these transmitted oscillations are regeneratively amplified.

The superimposed current flowing in this output circuit varies in amplitude according to the modulations impressed upon the carrier wave at the sending station, and there appears in the circuit of the primary winding 75 of the intervalve transformer 74, a unidirectional current having the frequency and characteristics of the modulated lower supersonic frequency produced by the modulation by the said lower supersonic frequency at the sending station. The frequency of the closed oscillatory circuit 78, 81 is tuned to the frequency of these variations by adjusting the condenser 81 comprising part of said circuit, and there is thus induced in this closed oscillatory circuit a current having the frequency of these variations and modulated by the audio signal modulator 34 of the sending station.

The slider 80 of the potentiometer 79 is so adjusted that the thermionic device 82 operates on the curved portion of its characteristic curve and thus the device 82 acts to detect or otherwise rectify these oscillations. There is thus produced in the output circuit of the said thermionic device, including the indicating device 83, superimposed currents corresponding to the lower supersonic frequency employed and varying in amplitude according to the signal currents impressed thereon. The unidirectional current corresponding to the envelope of these superimposed currents closed through the indicating device 83 causes it to produce sound waves or signals of the same character as those of the audio input.

In the operation of the receiving circuit of Fig. 4 the receiving element comprising antenna 90 is positioned so as to intercept Hertzian waves radiated from the antenna 41 of the sending station of Fig. 1. The circuit of the antenna 90 and the closed oscillatory circuit 92 coupled thereto are responsive to the radiated energy emitted from the send-

ing station, the tuning being suitably adjusted to the frequency of one of the side stations B or B' produced by the modulation of the output of the oscillator 10 by the lower supersonic frequency. The grid condenser 97 included in the grid circuit of the thermionic device 96 permits a negative potential to be built up upon the grid of said device so as to cause the device to be operated on the curved portion of its characteristic curve in the usual manner and thus to act to rectify or otherwise detect the oscillations, set up in the tuned circuit. Thus there is produced in the output circuit of the thermionic device 96 including the indicating device 83 superimposed currents corresponding in frequency to one of the side stations produced by the modulation of the carrier frequency by the lower supersonic frequency at the sending station and varying in amplitude according to the signal currents impressed on said lower supersonic oscillation by the input through transformer 8. The by-pass condenser 84 permits the flow of these superimposed currents and the unidirectional currents corresponding to the envelope thereof affects the indicating device 83 causing it to produce sound waves of the same character as the audio frequency at the transmitter. The indicating device 83 of course, may be a telephone receiver.

It will be seen that there is provided a signalling system particularly adapted for broadcasting service in which different classes of service may be rendered. The listener at the receiving station constructed in accordance with Fig. 4 or any other similar form of receiving station responsive merely to the fundamental wave frequency and the amplitude variations of an audible frequency impressed thereon, obtains a service which is subject to the usual interference by other stations within the range of his receiving apparatus. The user of the receiving station such as is shown in Fig. 3, however, obtains a de luxe broadcasting service which remains practically unresponsive to the energy emitted by broadcasting stations other than the one intended to hear. Even though the frequency of the fundamental or continuous wave is nearly the same, as for example 360 meters or 833,000 cycles per second and 364 meters or 824,000 cycles per second respectively, one of these series of waves being emitted from the sending station of the form shown diagrammatically in Fig. 1, the receiving station will be selectively responsive only to the sending station of the type disclosed herein and will remain inert to the energy emitted from the other sending station. In this manner the receiving station may readily listen in upon a concert or lecture of a relatively distant station if desired, even though a normally interfering broad-

casting sending station be located relatively near the receiving station.

Having thus described one embodiment of my invention, it is to be understood that the invention upon which this application is based is broader than the specific embodiments shown and described for the purpose of illustration, and that therefore it is to be limited only by the scope of the following claims:

1. The method of radio transmission comprising generating high frequency oscillations, generating lower supersonic frequency oscillations, modulating said lower supersonic frequency oscillations by an audio frequency, modulating the high frequency oscillations by such modulated lower supersonic frequency oscillations, preventing modulation of said high frequency oscillations by an audio frequency component, transmitting said modulated high frequency oscillations, receiving and detecting said high frequency oscillations and thereby reproducing said lower supersonic frequency oscillations detecting the latter named oscillations and obtaining thereby said audio frequency, independently receiving the side station produced by the modulation of the high frequency oscillations by said lower frequency oscillations, and detecting said side station, and producing thereby said audio frequency.

2. The method of radio transmission comprising generating high frequency oscillations, generating lower supersonic frequency oscillations, modulating said lower supersonic frequency oscillations by an audio frequency, modulating the high frequency oscillations by said modulated lower supersonic frequency oscillations while preventing demodulation of the modulated lower supersonic frequency oscillations thereby preventing modulation of said high frequency oscillations by an audio frequency component, transmitting said modulated high frequency oscillations, receiving and detecting said high frequency oscillations and thereby reproducing the lower supersonic frequency produced oscillations and detecting said oscillations and obtaining thereby said audio frequency.

3. The method of radio frequency transmission comprising generating high frequency oscillations, generating lower supersonic frequency oscillations, modulating said lower supersonic frequency oscillations by an audio frequency, modulating the high frequency oscillations by said modulated lower supersonic frequency oscillations, preventing modulation of said high frequency oscillations by an audio frequency component, transmitting said modulated high frequency oscillations, receiving the side station produced by the modulation of the high frequency oscillations by said lower frequency oscillations, and detecting said side station and reproducing thereby said audio frequency.

4. The method of radio transmission comprising modulating a low supersonic frequency series of oscillations by an audio frequency, modulating a high frequency series of oscillations by said modulated low supersonic frequency series of oscillations while preventing demodulation of the modulated low supersonic frequency oscillations thereby preventing modulation of said high frequency series of oscillations by an audio frequency component existing in said modulated low supersonic frequency series of oscillations, transmitting said modulated high frequency oscillations, receiving and detecting said high frequency oscillations and producing thereby said low supersonic frequency series of oscillations, detecting said low supersonic frequency series of oscillations and producing thereby the audio frequency.

5. The method of radio transmission comprising modulating a series of low supersonic frequency oscillations by an audio frequency, modulating a series of high frequency oscillations by said modulated lower supersonic frequency oscillations, preventing modulation of said high frequency by an audio frequency component, transmitting said modulated high frequency oscillation, receiving and detecting said high frequency oscillations and producing thereby said lower supersonic frequency oscillations, detecting said lower supersonic frequency oscillations and producing thereby said audio frequency, independently receiving and detecting the side station produced by the modulation of said high frequency oscillations by said lower supersonic frequency oscillations, and producing thereby said audio frequency.

6. The method of radio frequency communication comprising modulating a low supersonic frequency series of oscillations by an audio frequency, modulating a high frequency series of oscillations by said modulated low frequency oscillations, preventing modulation of said high frequency oscillations by an audio frequency component, transmitting said modulated high frequency oscillations, receiving and detecting the side station produced by the modulation of said high frequency by said lower supersonic frequency and producing thereby said audio frequency.

7. A radio communication system comprising a generator of high frequency oscillations, means for amplifying said high frequency oscillations, means for transmitting said amplified high frequency oscillations, a generator of lower supersonic frequency oscillations, means for amplifying said lower supersonic frequency oscillations, means for producing an audio frequency, means for audio modulating said lower supersonic frequency oscillations in accordance with said audio frequency, means for modulating said high frequency oscillations in accordance with said audio frequency.

8. A radio communication system comprising a generator of high frequency oscillations, means for transmitting said high frequency oscillations, a generator of lower supersonic frequency oscillations, means for producing an audio frequency, means for modulating said lower supersonic frequency oscillations in accordance with said audio frequency, means for utilizing said audio frequency, means for receiving a side station produced by the modulation of said high frequency by said lower supersonic frequency, means for detecting said side station and obtaining said audio frequency and a second means for utilizing said audio frequency oscillations.

9. A radio communication system comprising a generator of high frequency oscillations, means for transmitting said high frequency oscillations, a generator of lower supersonic frequency oscillations, means for producing an audio frequency, means for modulating said lower supersonic frequency oscillations in accordance with said audio frequency, means for modulating said high frequency oscillations by an audio frequency component comprising means for preventing demodulation of the modulated lower supersonic frequency oscillations, means for receiving said high frequency, means for detecting said high frequency and obtaining said lower supersonic frequency oscillations, means for detecting said lower supersonic frequency, and obtaining said audio frequency.

10. A radio communication system comprising a generator of high frequency oscillations, means for transmitting said high frequency oscillations, a generator of lower supersonic frequency oscillations, means for producing an audio frequency, means for modulating said lower supersonic frequency oscillations in accordance with said audio frequency.

frequency, means for modulating said high frequency oscillations by the audio frequency modulated lower supersonic frequency, means for preventing modulation of said high frequency oscillations by an audio frequency component, means for receiving a side station produced by the modulation of said high frequency by said lower supersonic frequency, means for detecting said side station and obtaining said audio frequency, and means for utilizing said audio frequency oscillations.

11. A radio communication system comprising a generator of high frequency oscillations, a generator of lower supersonic frequency oscillations, means for modulating said lower supersonic frequency oscillations in accordance with an audio frequency signal, an amplifier circuit comprising an electron discharge device having an input circuit and an output circuit, means for impressing said high frequency oscillations upon said input circuit, means for impressing said modulated supersonic frequency oscillations upon said output circuit for varying the characteristics thereof in accordance with said modulated supersonic oscillations whereby said high frequency oscillations are modulated by said modulated lower supersonic frequency oscillations without demodulation of said modulated supersonic frequency oscillations.

12. The steps in a method of radio transmission which comprise generating high frequency oscillations, generating lower supersonic frequency oscillations, modulating said lower supersonic frequency oscillations by an audio frequency, modulating the high frequency oscillations by said modulated supersonic frequency oscillations while preventing demodulation of the modulated lower supersonic frequency oscillations and transmitting said modulated high frequency oscillations.

13. In a signalling system, means for generating high frequency oscillations, means for generating intermediate frequency oscillations, a source of audio frequency energy, means for modulating said intermediate frequency oscillations by said audio frequency energy, means for modulating said high frequency oscillations by said modulated intermediate frequency oscillations, said last-named means comprising an electron discharge device arranged so as to act as an amplifier for said high frequency oscillations, the amplification factor of said amplifier being controlled in accordance with said modulated intermediate frequency by means in the output circuit of said amplifier for impressing said modulated intermediate frequency energy upon said output circuit whereby said high frequency energy is modulated by said modulated intermediate frequency without demodulation of said modulated intermediate frequency energy.
